UNITED STATES PATENT OFFICE.

EDWIN D. STALFORT, OF BALTIMORE, MARYLAND.

PUSH-BUTTON SWITCH.

992,077.

Specification of Letters Patent.

Patented May 9, 1911.

Application filed September 14, 1910. Serial No. 581,997.

To all whom it may concern:

Be it known that I, EDWIN D. STALFORT, a citizen of the United States, residing at Baltimore, in the State of Maryland, have invented new and useful Improvements in Push-Button Switches, of which the following is a specification:

This invention relates to electric switches of the push button type and it has for one of its objects to improve and simplify the construction and operation of switches of this character, so as to be reliable and efficient in use, composed of comparatively few parts and relatively inexpensive to manufacture.

Another object of the invention is the provision of a push button switch including a ratchet or star wheel contact, which has alternate teeth flanked with insulation so as to raise the fixed contact cooperating with the wheel out of engagement therewith by each alternate step in the movement thereof so as to successively open and close the circuit by successively pressing the button which operates to control the wheel.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a central vertical section of the switch. Fig. 2 is a plan view thereof with the cover removed. Fig. 3 is a perspective view of the make or break ratchet wheel or movable contact element. Figs. 4 and 5 are detail views, showing the position of the parts when the circuit is open and closed.

Similar reference characters are employed to designate corresponding parts throughout the several views.

Referring to the drawing A designates a casing made of porcelain or other suitable insulating material and constructed in any simple manner. In the top of the casing is a button 1 that is normally pressed upwardly and is adapted to be pushed inwardly in operating the switch. Within the casing is a spring contact 2 to which one wire 3 of the circuit is connected and co-acting with this spring contact is a movable contact 4, in the form of a star or ratchet wheel, which rotates on an axle 5 secured to a post or

standard 6 fastened to the base or bottom of the casing. The free end of the contact 2 is adapted to ride on the teeth of the movable contact and thereby close the circuit. The post and axle are preferably of metal and at the base of the post the other circuit wire 7 is connected.

Extending transversely across the top of the casing and located between the contact wheel and inner end of the push button is a spring pawl 8 fastened at 9 to the casing, one end of the leaf spring forming the pawl being bent downwardly so that the free end thereof will engage the contact wheel. The spring pawl holds the push button normally outward and when the button is pushed inwardly the spring yields and causes the contact wheel to move one tooth. The spring contact 2 not only forms a conductor for current but operates as a back acting or hold back pawl for preventing the contact wheel from moving reversely as the spring pawl returns to normal position when the pressure on the push button is relieved.

Fastened to one side of the contact wheel is a correspondingly shaped wheel 10 of insulation. The alternate teeth 11 of this insulation are raised above the corresponding teeth of the contact wheel, while the intermediate teeth 12 are flush with the adjacent teeth of the contact wheel. The effect of this is that as the rotary element of the switch turns step-by-step the spring contact 2 will complete the circuit when it engages the teeth of the metal section of the element that are flush with the insulation and open the circuit when it engages the teeth of the insulation raised above the metal section of the element. It will thus be seen that the circuit is made and broken by a single element that is moved one step each time the button of the switch is pressed.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:

1. In a switch, the combination of a rotary element including metal and insulation sections each formed with ratchet teeth, the alternate teeth on the insulation section being raised above the corresponding teeth upon the metal section, a spring contact arranged to engage alternately a tooth of one section and a tooth of the other section as the element is moved step-by-step, and an actuator arranged to engage the teeth of the element to turn the same step-by-step.
2. A switch comprising a rotatable element in the form of a ratchet wheel formed of conducting and non-conducting parts, the alternate teeth of the non-conducting part being raised above the corresponding teeth of the conducting part, a contact spring arranged to engage the teeth of the element to complete and break the circuit by the alternate engagement of the teeth of the conducting and non-conducting parts, said spring being arranged to form a hold back pawl, and an actuating pawl arranged to engage the teeth of the said element to turn the same step-by-step.
3. A switch comprising a rotatable element in the form of a ratchet wheel formed of conducting and non-conducting parts, the alternate teeth of the non-conducting part being raised above the corresponding teeth of the conducting part, a contact spring ar-

ranged to engage the teeth of the element to complete and break the circuit by the alternate engagement of the teeth of the conducting and non-conducting parts, said spring being arranged to form a hold back pawl, an actuating pawl arranged to engage the teeth of the said element to turn the same step-by-step, and a push button for operating the last mentioned pawl.

4. In a switch, the combination of a casing, a rotating element mounted therein and consisting of toothed conducting and non-conducting parts, the alternate teeth of the non-conducting parts being raised above the corresponding teeth of the conducting part, means for connecting the conducting part to the circuit, a spring contact engaging the element to form a pawl and adapted to complete the circuit by contact with the conducting part and to break the circuit by contact with the raised teeth of the non-conducting part, a spring arranged within the casing and forming a pawl for engaging with and turning the said element step-by-step, and a push button arranged to operate through the said spring for turning the element.

In testimony whereof I affix my signature in presence of two witnesses.

EDWIN D. STALFORT.
